COMB

Bernard M. Schweizer, Nashville, Tenn., assignor
of one-half to Eisele & Company, Nashville,
Tenn.

Application June 13, 1947, Serial No. 754,356

2 Claims. (Cl. 132—28)

1

This invention relates to hair combs, the primary object of the invention being to provide a comb of this type so constructed as to permit cleaning thereof with unusual ease.

As is well known, accumulations of dirt and the like result through regular use of combs of conventional construction, these accumulations occurring in the several crotches defined by the intersection of the teeth of the comb with the back piece thereof. It is further well known that removal of these accumulations is a troublesome and difficult task, since they are such that mere irrigation of the comb is not sufficient, and it is necessary in conventionally-formed combs usually to remove each accumulation separately.

In the present invention, the comb, stating the invention briefly, is equipped with a cooperating cleaning member having spaced teeth that extend through and beyond the crotch portions of the comb, coinciding between the regular teeth. In the invention, the accumulations of dirt and other foreign matter form on the teeth of the cleaning member. The comb and cleaning member are so constructed, in this connection, that the cleaning member is adapted for an unusual movement, in cleaning the comb, in a line parallel to the regular teeth of the comb, and thus the accumulations are readily removed during the action to be described in detail hereinafter, since they are caused to occur on portions of the comb which are made movable with respect to each other. By using the cleaning member as described, all accumulations are simultaneously fully dislodged, and easily washed away with a small amount of irrigation.

small amount of irrigation.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing:

Figure 1 is an elevational view, with a portion removed, of a comb constructed in accordance with the invention.

Figure 2 is a view taken on line 2-2 of Figure 1.

Figure 3 is a fragmentary side elevational view of a slidable cleaning member embodied in the invention.

Referring to the drawing in detail, the reference character 5 generally designates the comb

proper, that is formed with the customary enlarged end teeth 6 and intermediate teeth 7. In the embodiment of the invention illus-

In the embodiment of the invention illustrated, a comb is shown that has only one type of intermediate teeth these being in the nature of coarse or widely spaced teeth. However, this type of comb is shown purely for the purpose of illustrating the invention, and as will be apparent hereinafter, the comb can be of the type having both coarse and fine teeth, and can in fact be adapted to the construction of most types of conventional hair combs.

The back of the comb 5 has been shown at 8, and as well known, the lower portion thereof, in conjunction with the intermediate teeth 7, defines a plurality of crotches 9 disposed between the various teeth 1. In conventional combs, as is well known, accumulations of dirt or other foreign matter tend to occur in these crotches. They are customarily removable only by the use of a sharp, pointed object, accompanied by irrigation under considerable pressure.

In the invention, a longitudinal groove or channel 10 is provided in the back 8 of the comb 5, that preferably extends from end to end thereof, this groove 10 preferably being of inwardly tapering formation when viewed in cross section, as is apparent from Figure 2.

By the provision of this groove, it is seen that longitudinal shoulders 11 are defined on either side of the upper end of the groove, extending from end to end of the back 8.

In depth, the groove 10 extends below the bottom edge of the back 8, into the upper portions of the several intermediate teeth 7, as shown at 12 in Figure 2.

The outer surfaces of the upper portions of the end teeth or posts 6 are flat, as shown at 13, and intersect the top edge of the back 8 at right angles thereto, these defining end shoulders.

40 **Mounted on the comb 5 is a cleaning member 14, that comprises a back piece 15 extending longitudinally of the comb 5, and positioned above the top edge of the back 8 of the comb, defining a hand grip. At its ends, this is provided with downwardly extended guiding fingers 16, that are positioned beyond the respective end shoulders 13 of the comb 5, as clearly shown in Figure 1. The inner surfaces of the fingers 16**

45 **are flat, to correspond to the formation of the end shoulders 13 of the comb 5, and are slidably relative thereto, in lines parallel to lines drawn longitudinally through the center of the intermediate teeth 7.**

50

Additionally, the cleaning member 14 is pro-

vided at the sides of its longitudinal inner surface with longitudinal shoulders 17 that normally engage the shoulders 11 of the back 8. Between the shoulders, and extended longitudinally of the cleaning member, is a depending rib 17'. At spaced intervals, a plurality of cleaning teeth 18 extend downwardly from the rib 17' of the cleaning member, into the groove 10. In cross-section, these are each of tapering formation, corresponding to the taper of the groove 10, 10 and fit snugly therein.

The cleaning teeth 18 are so formed on the cleaning member 14, and spaced relative to the teeth 7 of the comb proper as to result in each cleaning tooth coinciding between adjacent intermediate teeth 7, as best shown in Figure 1. As a result, they constitute in effect extensions into the crotches 9. During normal use of the comb, with the cleaning member mounted thereon as shown in Figure 1, accumulations of dirt and foreign matter will obviously, therefore, tend to occur on the ends of the cleaning teeth.

During normal use of the comb, it may be preferable to retain the cleaning member in locked position relative to the comb proper, and as one example of how this may be accomplished, I provide a lock pin 19, received in a transverse opening extending through the back 8 of the comb 5, and through the rib 17' of the cleaning member 14.

In use of a comb constructed in accordance with the invention, the lock pin 19 is removed, freeing the cleaning member 14 for slideable movement relative to the comb 5. The movement in question is effected in a line parallel with a line drawn longitudinally through the center of any of the teeth 7, that is, the cleaning teeth 18 are moved in lines parallel to the teeth 7. In effecting such movement, the back piece 15 is gripped, in one hand, while the comb 5 is gripped in the other hand. They are alternatively moved apart and toward each other, with the inner shoulder of the guiding fingers 16 sliding on the end shoulders 13. In conjunction with this movement, irrigation may be employed. However, it is seen that the main cleaning action results from dislodgement of the dirt accumulation from the end of each cleaning tooth 18, as the tooth is withdrawn from the crotch 9 into which it extends. All the accumulations are, as a result, simultaneously removed, and additionally, throughout the cleaning action, are kept separate one from the other, and all tendency thereof to become embedded in the groove 10 itself is effectively prevented.

The dislodging of the several accumulations, by a cleaning action permitted with a comb constructed as set forth, is effected almost immedi-

ately, upon one or two movements of the parts of the comb relative to each other. This, as will be readily seen, is by reason of my particular construction, whereby, when the cleaning member 14 is properly positioned as shown and described, there is a complete and simultaneous meshing of all its cleaning teeth 18 from end to end thereof, with the teeth of the comb 5, thus creating full penetration and permitting thorough cleaning by a simple up and down movement.

After the above operation, if desired, the cleaning member 14 can be withdrawn completely, and the groove 10 irrigated to complete the cleaning.

The cleaning member is then returned to position, and the lock pin 19 again inserted.

What is claimed is:

1. A comb, comprising a back having a longitudinal groove, end and intermediate teeth on the back, said groove extending in depth below the meeting line of the back and teeth, and a cleaning member mounted on the back for movement into and out of the groove in lines parallel to the teeth, said member comprising a back piece, depending guiding fingers on the ends thereof extending along the outer surfaces of and slidably engageable with the respective end teeth, and cleaning teeth on the back piece, each cleaning tooth being extended into the groove between adjacent intermediate and end teeth of the comb.
2. A comb, comprising a back having a longitudinal groove, end and intermediate teeth on the back, said groove extending in depth below the meeting line of the back and teeth, a cleaning member mounted on the back for movement into and out of the groove along lines parallel to the teeth, said member comprising a back piece, depending guiding fingers on the ends thereof, said fingers being positioned beyond the respective end teeth and being slidably engageable with the outer surfaces of the end teeth, cleaning teeth on the back piece, each cleaning tooth being extended into the groove adjacent intermediate and end teeth of the comb, and a removable locking means extending between the cleaning member and the back.
